UNITED STATES PATENT OFFICE

EDWARD C. SASSER, OF WASHINGTON, DISTRICT OF COLUMBIA

SHAVING MUG

Application filed August 4, 1928. Serial No. 297,472.

My invention relates to new and useful improvements in shaving mugs and has for an object to provide a shaving mug which, primarily, consists of two chambers, one of 5 which is substantially air-tight so that when the warm water is placed in the one compartment the air will be heated in the other compartment, and the small film or particles of water that adhere to the dividing wall will be retained in their heated condition due to the heated air in the lower chamber.

Still another object of the invention is to provide a shaving mug having two compartments, one of which is substantially air-tight 15 and the upper compartment being provided with a lid, to the inner portion of which may be fastened or temporarily secured, a separate container holding shaving powder or shaving cream.

20 Still another object of the invention is to provide a shaving mug comprising, primarily, two compartments and having a dividing wall between the two compartments with a roughened upper surface so that small 25 drops or particles of water will adhere thereto and the heated air and the heated wall will cause the drops or particles of water to retain their heat and thus provide a better lather when the brush is inserted and picks up the heated particles of water, said roughened surface also acting as a means for aiding in the beating or whipping of the soap for materially increasing the number of air 30 cells in the soap and decreasing the size of 35 the air cells.

Still another object of the invention is to provide a modified form of shaving mug wherein the lower compartment, if desired, may be accessible so that used razor blades 40 may be placed therein if so desired.

With these and other objects in view, the invention consists of certain new and novel features and combination of parts as will be hereinafter more fully described and pointed 45 out in the claims.

Referring now to the drawings showing a preferred form and several modifications thereof:—

50 Fig. 1 is a sectional view of one form of shaving mug showing the two compartments

and an integral chamber carried by the lid for holding soap powder;

Fig. 2 shows a shaving mug, part of the same being broken away for clearness of illustration and showing a lower compartment 55 of a slightly different shape,

Fig. 3 is a vertical sectional view of a shaving mug similar to the one shown in Fig. 1, the cover however showing a clip for holding a tube of shaving soap,

Fig. 4 is a fragmentary sectional view of the form shown in Fig. 3 but taken at right angles thereto,

Fig. 5 is a fragmentary vertical sectional view showing a cover carrying a detachable 65 chamber for holding the soap powder,

Fig. 6 is a view of a slightly modified form, wherein the partition wall is formed of glass,

Fig. 7 is a vertical sectional view of a slightly modified form showing an integral 70 glass partition and a lower chamber being provided with a detachable bottom,

Fig. 8 is a plan view of the metal partition wall as used in several of the forms,

Fig. 9 is a plan view of a slightly modified form of partition wall,

Fig. 10 is a fragmentary sectional view showing a perforate and an imperforate wall and

Fig. 11 is a side elevation showing a mug 80 provided with projections on its outer surface to prevent the same from slipping from the hand.

Referring now to Fig. 1 there is shown a mug which may be formed of glass or china or any other suitable material, the diameter of the same may be from two to four inches or might be even larger, if desired.

The upper peripheral edge of the mug is provided with threads 3 so that a metal cover 4 may be threaded thereon when the mug is not in use. As shown in Fig. 1, this cover may be provided with a downwardly depending chamber 5 which in this instance is conical in shape, and this chamber 5 is provided with a revolvable cap 6 so that the openings 7 in the chamber and cap may register when the cap is turned to thus drop a little soap powder 8 on the partition wall 9.

It will be seen that by providing this par-

tion wall 9 the mug is divided into two chambers, that is, the upper chamber 10 and the lower chamber 11.

Referring now to the partition wall 9 in this instance it comprises a metal disc as may be seen in Fig. 8 having the upstanding lugs or short projections 12 as may be seen in the several views. The object in roughening the upper surface of this disc 9 is so that the particles of water will adhere to the roughened surface of this disc. A small ledge 13 is formed in the interior of the mug at a point that divides the chamber 10 from the chamber 11, and the disc is of such diameter that it may be wedged tightly down in the mug and tightly on the seat or ledge 13. Now when it is desired to use this mug the cover may be removed and hot water poured into the chamber 10 which will heat the metal disc and will also tend to heat the air in the chamber 11.

The water may be then poured from the chamber 10 and a little soap powder released on the disc. A little water will remain on the disc, the particles clinging to the roughened surface and these particles will be kept warm by the heat of the disc and the heated air in chamber 11. The brush will be inserted in the upper chamber of the mug and absorb the heated particles of water and these heated particles of water will aid in the chipping of the soap so that a fine lather will be obtained.

In Fig. 2 a similar form of shaving mug is shown with the exception that the chamber 11' that corresponds with the chamber 11, is decreased in area due to the fact that the bottom wall 14 is raised as may be clearly seen from Fig. 2.

Referring now to the slightly modified forms as shown in Figs. 3 and 4, the mug in this instance is similar to that shown in Fig. 1 except that the cover 4' is provided with a clip 15 in which a tube 16 of shaving soap may be inserted and when this cream is used up a new tube of cream may be secured rather than buy the whole new shaving mug.

Referring now to the Fig. 5, a shaving mug similar to that of Fig. 3 will be seen but in this instance, the cover 17 of the mug 18 is provided with a central opening 19 in which may project a stem 20, which stem is formed on the bottom of a container 21, which container is adapted to hold the shaving powder 22. In other words, in this form a detachable container for shaving soap may be carried in the shaving mug rather than a tube of shaving cream as shown in Figs. 3 and 4.

Referring now to Fig. 6, there is shown a shaving mug 25 and in this instance the partition wall or disc 26 is formed of glass and the sides of the partition wall or disc 27 are slightly tapered to wedge in the mug so that the upper chamber 28 is provided as well as the lower chamber 29.

In Fig. 7, another slightly modified form is shown wherein the mug 30 has the integral partition wall 31 which divides the chamber 32 from the chamber 33, and in this instance a detachable bottom 34 is provided so that the old razor blades (not shown) may be carried in this chamber 33, if desired. A cover 35 is shown carrying the integral soap chamber 36 but it will be understood that the cover might be of the form shown in Figs. 75 or 5, if desired.

In Fig. 9, I have shown a slightly modified form of the partition wall or disc 37 which might be glass or metal, and in this instance, the roughened surface is provided by having the ribs 38 extending at right angles to each other as forming the little squares 39.

In Fig. 10 is shown a fragmentary portion of the mug 40, there being two chambers 41 and 42 and the partition wall in this instance comprises the two plates 43 and 44, the first mentioned being imperforate and the second mentioned being perforated to thus provide the upper roughened surface.

Instead of having the outside of the mug smooth as shown in the first ten figures, the same might be roughened as shown in Fig. 11, that is the outer surface 45 might be provided with the little tits 46 or other slight projections to thus prevent the mug from slipping from the hand.

From the foregoing it will be seen that I have provided a shaving mug consisting primarily, of two chambers, one of which is substantially air-tight, and the partition wall between two chambers having a roughened surface so that the particles of water will cling thereto and due to the heat formed in the lower chamber, will keep these particles of water in a heated condition for some time.

It will also be shown that I have utilized the lid for carrying the soap powder or shaving cream and these compartments may be either integrally formed with the lid or the lid may be so formed as to receive refills or new tubes or containers of soap powder or shaving cream.

Many slight changes might be made without departing from the spirit and scope of the invention.

Having thus described my invention, what I claim as new and desire to hereby secure by Letters Patent is:—

1. A shaving mug, a partitioned wall roughened on its upper surface and dividing the mug into two chambers, one of which is substantially air-tight whereby the air in the one chamber will be heated when a heating agent is applied to the partition wall and adapted to keep particles adhering to said partition wall in heated condition.

2. A shaving mug having a partition wall therein to divide the mug into two chambers, one of which is substantially air-tight, the

upper surface of the wall being roughened, a cover for the mug and soap holding means carried by the said cover.

3. A shaving mug having a partition wall 5 in its lower portion and dividing the mug into two chambers, one of which is substantially air-tight, the said partition wall having a roughened upper surface whereby particles of a heating agent may cling to the 10 said roughened surface; a removable cover for the mug and a container supported by the cover and extending down into the first chamber and said container adapted to hold a lather-producing material.

15 4. A shaving mug with a partition wall dividing the mug into an upper and lower chamber, the lower chamber being substantially air-tight, the said partition having a roughened upper surface; a detachable cover 20 for the mug with means on the undersurface of the cover for supporting shaving soap.

5. A shaving mug having a roughened exterior surface and an interior partition wall dividing the mug into two chambers, one of 25 which is substantially air-tight and adapted to retain a heating agent; a cover for the mug and having means for carrying soap releasable upon the wall, and a detachable bottom for the said air-tight chamber.

30 6. A shaving mug having a partition wall dividing the interior of the mug into superposed chambers, a cover for the mug having means disposed toward the wall for releasably retaining soap, and a detachable bottom 35 for the nether chamber.

In testimony whereof I affix my signature.
EDWARD C. SASSER.
